United States Patent Office

Des. 194,031
Patented Nov. 13, 1962

194,031

CHAIR

George B. Jensen and Ronald W. Lane, Chicago, Ill., and Wayland B. Parker, Olean, N.Y., assignors, by mesne assignments, to Daystrom, Incorporated, Murray Hill, N.J., a corporation of Texas

Filed Jan. 16, 1961, Ser. No. 63,571

Term of patent 7 years

(Cl. D15—1)

FIG. 1

FIG. 2

FIG. 3

FIG. 4

FIGURE 1 is a front perspective view of a chair embodying our design;

FIGURE 2 is a front elevational view;

FIGURE 3 is a side elevational view; and

FIGURE 4 is a top plan view thereof.

Except for the differences in its curvature as seen in the drawings, the rear of the back rest panel is substantially the same in appearance as the front thereof.

We claim:

The ornamental design for a chair, substantially as shown and described.
